LADY'S STOCKING

Richard W. Nordman, Charlotte, N. C., assignor of fifty per cent to Creston Full Fashioned Hosiery Mills, Inc., Charlotte, N. C., a corporation of North Carolina, and fifty per cent to The Lockwood-Butler Company, Charlotte, N. C., a partnership

Application May 1, 1951, Serial No. 15,032

Term of patent 14 years

(Cl. D47—7)

To all whom it may concern:

Be it known that I, Richard W. Nordman, a citizen of the United States of America, residing at Charlotte, in the county of Mecklenburg, State of North Carolina, have invented a new, original, and ornamental Design for a Lady's Stocking, of which the following is a specification, reference being had to the accompanying drawings, forming a part thereof.

Figure 3 is an enlarged fragmentary elevation of the upper portion of the high splice portion of the stocking.

The design is characterized by three lines of parallel picot stitches extending along the forward edges of the heel and high splice but spaced slightly rearwardly of said forward edges and the center line of each set of picot stitches having twice as many picot stitches therein as the other lines of picot stitches.

I claim:

The ornamental design for a lady's stocking, substantially as shown and described.

RICHARD W. NORDMAN.
